[57] **CLAIM**

The ornamental design for a round-post electric fence
insulator, substantially as shown.

DESCRIPTION

FIG. 1 is a rear perspective view of a round-post elec-
tric fence insulator embodying our new design;

FIG. 2 is a rear elevational view thereof;

FIG. 3 is a top plan view thereof;

FIG. 4 is a side elevational view taken from the right in
FIGS. 1 and 2;

FIG. 5 is a bottom plan view thereof, and

FIG. 6 is a front elevational view thereof.
